UNITED STATES PATENT OFFICE.

JOHN NOWAKOWSKI, OF MILWAUKEE, WISCONSIN, ASSIGNOR OF ONE-HALF TO STEVE LUKASZEWICZ, OF MILWAUKEE, WISCONSIN.

BURGLAR ALARM.

Application filed October 9, 1923. Serial No. 667,464.

To all whom it may concern:

Be it known that I, JOHN NOWAKOWSKI, a citizen of the United States, and resident of Milwaukee, in the county of Milwaukee and 5 State of Wisconsin, have invented certain new and useful Improvements in Burglar Alarms; and I do hereby declare that the following is a full, clear, and exact description thereof.

10 This invention pertains to burglar alarms and more particularly to a device adapted to operate a signal upon the insertion of a key or implement into a doorlock.

The primary object of the invention resides in the provision of a device of the 15 above character adapted to be inserted into the lock of a door, which will close an electric circuit and operate either a visible or audible signal, should the device be engaged by a tool or any form of implement 20 inserted into the lock.

With the above and other objects in view, which will appear as the description proceeds, the invention resides in the novel 25 construction, combination and arrangement of parts, substantially as hereinafter described and more particularly defined by the appended claim, it being understood that such changes in the precise embodiment 30 of the herein disclosed invention may be made as come within the scope of the claim.

In the accompanying drawing is illustrated one complete example of the physical embodiment of the present invention constructed according to the best mode so far devised for the practical application of the principles thereof.

In the drawings:—

40 Figure 1 is an elevational view partly broken away and in section to more clearly illustrate the structural details, and

Figure 2 is a transverse sectional view taken on the line 2—2 of Figure 1.

Referring more particularly to the accompanying drawings, the present invention is designed in the form of a key comprising a hollow shank 1 provided at one end with a lock operating projection 2 and at the other end with an enlarged hollow head 3 which is split for the purpose of reducing the cost of manufacture and allowing removal of the mechanism carried within the head. The cover 4 is secured to that portion of the head carried by the key, by 55 means of screws 5.

Slidably mounted within the shank 1 and normally projecting slightly therefrom is a plunger 6 provided with a head disposed within the casing 3 and adapted to engage a contact member 7 secured to the insulating 60 block 8 mounted within the casing. A second contact 9 is positioned adjacent the contact 7 and is also insulated from the casing by the block 8.

Connected with the contacts 7 and 9 is 65 an electric circuit 11 illustrated in diagrammatic form in connection with Figure 1. This circuit is provided with the customary battery, or other source of electrical supply B, and an audible signal, such as the bell C. 70 In addition to the foregoing the circuit may be provided, when so desired, with a visible signal, in the form of an incandescent light, D.

From the foregoing description taken in 75 connection with the drawing it will be obvious that when the shank 1 is positioned within the lock of a door, any tool or implement inserted from the opposite side, for the purpose of turning the key prior to 80 forcing it out of the lock, will engage the projecting end of the plunger 6 causing the same to move longitudinally within the shank whereupon the contact 7 engages the contact 9, closing the circuit 11 and actuating 85 the desired signals. It will also be observed that the present invention, being constructed in the form of a key, will in no way interfere with the operation of the 90 door from that side which carries the device. Consequently its removal, in order to lock or unlock the door, is eliminated.

I claim:—

A device of the class described comprising 95 a door key having a hollow shank, a lock operating projection at one end of said shank, an oval shaped handle at the other end of said shank and having an opening concentric with the opening in said shank, said handle being formed of two cup-shaped 100 parts, the inner of said parts being rigid with said shank, the outer of said parts being detachable and provided with a centrally located opening, screws securing the outer part to said inner part, a plunger 105 slidably mounted within said shank and having an end projecting from the outer end of said shank and having an enlarged head at its rear end positioned within the inner part of said handle, an insulating 110

block secured within the inner part of said handle and having an opening surrounding the enlarged head of said shank, a contact spring carried by said block and bearing against the end of said head, a second contact spring secured to said block and located behind said first mentioned spring, and conductors connected to said spring

and passing through the aperture in the outer portion of said handle.

In testimony that I claim the foregoing I have hereunto set my hand at Milwaukee, in the county of Milwaukee and State of Wisconsin.

JOHN NOWAKOWSKI.
